SHORT WAVE APPARATUS

Felix Herriger, Berlin, Germany, assignor to Tele-funkens Gesellschaft für Drahtlose Telegraphie m. b. H., Berlin, Germany, a corporation of Germany

Application September 2, 1938, Serial No. 228,089
In Germany September 2, 1937

2 Claims. (Cl. 250—151)

This invention is concerned with means adapted to the generation or the amplification of oscillations, especially oscillations of ultra high frequencies.

5 It is a well known fact that serious difficulties arise in the operation of master-driven ultra short wave generators or oscillators in general, especially where the generation of wavelengths is concerned which are of the decimeter or centimeter range. On the other hand, however, extremely great frequency stability is obtainable with this kind of control. It has been suggested in the art to use cathode ray tubes for the 10 generation of oscillations and to produce the radio frequency current by periodically directing the focussed or beamed discharge current to two or more anodes known as collector or gathering electrodes. A discharge tube of this type contains the following elements: A cathode which 15 is the source of the electrons, means designed to insure concentration or focussing of the electron pencil or beam, say, a stop or diaphragm, electrostatic deflector plates for the control of the cathode ray pencil passed between them, and two gathering electrodes maintained at a positive potential. The control potential is applied to the 20 said deflector plates, while the output circuit tuned to a frequency twice the control frequency is united with the two gathering electrodes. It is also known in the art to retard the pencil or 25 jet of electrons before it is passed through between the control plates with a view to enhancing its deflectibility or deflection sensitivity. However, such schemes are unserviceable for drive or control action with ultra high frequencies. One reason for the failure of the arrangement in 30 this regard resides in the finite rate of propagation speed of the electron pencil; another reason lies in the extension of the plate-shaped electrodes used for deflection. In fact, it has already been recognized and admitted that Braun tubes of the conventional type are for these reasons unsuited for oscillographing ultra-short waves. It 35 has been attempted to overcome the foregoing difficulty by subdividing the deflector electrodes into several pairs of plates. This remedy, however, is imperfect because a tube of such a design will operate under optimum conditions only for 40 very definite frequencies and working potentials. A cathode ray tube is rendered controllable by ultra high frequencies, according to the present invention, by the use of short deflector fields. The term "short deflector field" refers to that 45 time which the electron requires to pass through the control field which is small compared with

the duration of a period of the working frequency; in other words, only one-tenth of the period. In order to insure high deflection sensitivity, the electrons are subjected to a retarding action in the immediate neighborhood of the 5 control zone.

The basic idea of the invention shall now be described in more detail by reference to the appended drawing. 1 denotes the evacuated discharge vessel. At one end thereof there is mounted an optionally indirectly heated cathode 2 within a focussing electrode 3 (Wehnelt cylinder or shield). The electron pencil 4 is accelerated by a gun or anode 5 in the form of a stop or diaphragm and maintained at a positive potential, 10 and by one or more electrical lenses 6, 6' which consist of two cylinders kept at constant potentials, the potential of 6 being higher than that of the diaphragm 5, while the potential of 6', in turn, lies above the potential of 6; or else by similarly acting magnetic lenses the pencil is again focussed so that it will finally impact upon the retarding electrode 7 which, for instance, is of 15 spherical or conical shape and which is maintained at a potential being negative relative to 20 the cathode. The result is that the electrons come to a stop a short distance anteriorly of the retarding electrode so that they may then be acted upon in an effective manner even with extremely low control potentials. For control are 25 used two auxiliary electrodes 8 and 8' which are impressed with ultra high frequency alternating potential and optionally also with a negative biasing voltage. In shaping this auxiliary or accessory electrode, care must be taken so that a 30 "short" field will be set up; in other words, that a field of appreciable intensity will be present and act only on a short distance of the cathode ray pencil path. The said auxiliary electrodes consist, for instance, of two wires (placed perpendicularly on the plane of the drawing) or of strips of sheet metal placed on edge and which, if desired, may have the edges facing each other sharpened. According to the polarity at a given instant of the auxiliary electrodes 8, 8', the electron pencil will be deflected to one of the two arms 9, 9' of the discharge vessel 1, thus striking the gathering or impactor electrodes 10, 10' mounted therein. The latter are impressed with 35 a high positive potential and they are united with 40 the output circuit which comprises a condenser 11 and a coil 12, for instance, and which is tuned to a frequency twice the control frequency. The ultra high frequency is fed to a dipole antenna 14, 14' through the intermediary of a coupling 45 50 55

coil 13. It will be understood that the inductances 12, 13 are chosen low in view of the shortness of the waves; in fact, under certain circumstances they may consist of simple wire loops. 5 Between the auxiliary electrodes 8 and 8' and the gathering electrodes 10 and 10', respectively, additional accelerator electrodes or guns, screen grids, etc., may be mounted if required; also electronic multiplier stages may be there interposed. 10 The tube of the present invention offers the advantage over prior types of discharge arrangements conceived for the same purpose that the cathode ray pencil is actually able to follow and respond to the ultra high frequency control potential. 15 And this situation holds true not merely for a single wavelength but, in fact, it is independent of the working frequency. This result is obtained because of the use of a short control field and of the accumulation or baffling of the 20 electrons inside the control zone. The use of narrow control electrodes presenting a dimension which is small in the sense of the pencil, moreover offers the advantage that the capacity between these electrodes is low so that it is an easy 25 matter to maintain a high control potential. The consequence is that the use of a comparatively high control potential will offset and compensate for the short time of action upon the pencil. If the control electrodes are of appreciable 30 length in the direction of the pencil—and this has invariably been true of the conventional types of tube—the transit time required by the electrons for passing the interelectrode gap is comparable with the period of the ultra high frequency. 35 Imagining a short piece to be cut out of the electronic pencil and tracing the same en route through the control space, it will be found that the control effects during the stay inside the control space cancel out. However, this is not 40 liable or possible to occur in this invention because of the shortness of the field.

The basic idea of the invention is not confined to the exemplified embodiment here shown and described. It goes without saying that the tube 45 is usable also for lower frequencies. Moreover, the number of collector electrodes may be raised, and the electron pencil may be imparted a rotary motion by convenient disposition of the control electrodes, with the result that it will describe the shell of a cone and will sequentially impinge upon 50 the different gathering electrodes. In this man-

ner, multiphase currents are producible, and high frequency multiplications are feasible.

What is claimed is:

1. A cathode ray tube comprising an envelope containing a source of electrons at one end thereof, a pair of spaced electron collecting electrodes at the other end of said envelope for receiving said electrons, a plurality of accelerating electrodes located between said source and said collecting electrodes, and electron deflecting electrodes located on opposite sides of the path of travel of the electron stream and between said accelerating electrodes and said collecting electrodes and adapted to have an alternating current potential applied thereto, and a decelerating electrode positioned adjacent said deflecting electrodes but on the opposite side thereof from said accelerating electrodes, said deflecting electrodes comprising thin conductors transverse to the beam and adjacent to the path of travel of the electrons whereby the effective surface of said deflecting electrodes transverse to the beam is substantially negligible compared to the distance between said source of electrons and said decelerating electrode, the time required for electrons 20 to pass through the field set up by said deflecting electrodes being of short duration compared to a period of time of one cycle of alternation of said applied alternating voltage. 25

2. A cathode ray tube comprising an envelope 30 containing a source of electrons at one end thereof, a pair of spaced electron collecting electrodes at the other end of said envelope for receiving said electrons, an accelerating electrode and electron deflecting electrodes in the order named 35 positioned between said source of electrons and said collecting electrodes, a decelerating electrode positioned adjacent said deflecting electrodes but on the opposite side thereof from said accelerating electrode, said deflecting electrodes being located on opposite sides of the path of travel of the electron stream and adapted to have an alternating voltage applied thereto, said deflecting electrodes comprising strips of sheet metal positioned transversely and perpendicularly to the path of travel of the electrons whereby the time required for an electron to pass through the field set up by said deflecting electrodes is short compared to the period of time of one cycle of alternation of the applied voltage to the deflecting 40 electrodes. 45 50
